(57) **CLAIM**

The ornamental design for a latch, as shown and described.

DESCRIPTION

Cross-reference is made to U.S. Design patent application Ser. No. 29/585,272 titled "Cooler," filed Nov. 22, 2016, and U.S. Utility patent application Ser. No. 15/819,950 titled "Cooler", filed Nov. 21, 2017, all of which are expressly incorporated herein by reference.

FIG. 1 is a front perspective view of a first embodiment of a latch design;
FIG. 2 is a front elevation view of the design of FIG. 1;
FIG. 3 is a rear elevation view of the design of FIG. 1;
FIG. 4 is a left side elevation view of the design of FIG. 1, the right side elevation being a mirror image of FIG. 4;
FIG. 5 is a top plan view of the design of FIG. 1;
FIG. 6 is a bottom plan view of the design of FIG. 1;
FIG. 7 is a front perspective view of a second embodiment of a latch design;
FIG. 8 is a front elevation view of the design of FIG. 7;
FIG. 9 is a rear elevation view of the design of FIG. 7;
FIG. 10 is a left side elevation view of the design of FIG. 7, the right side elevation being a mirror image of FIG. 10;
FIG. 11 is a top plan view of the design of FIG. 7; and,
FIG. 12 is a bottom plan view of the design of FIG. 7.
The broken lines illustrating portions of the latch form no part of the claimed design.
